UNITED STATES PATENT OFFICE

ROBERT C. SIMPSON, OF GROTON, CONNECTICUT, ASSIGNOR TO ELECTRIC BOAT COMPANY, OF GROTON, CONNECTICUT, A CORPORATION OF NEW JERSEY

SUBMARINE BOAT

Application filed December 21, 1926. Serial No. 156,130.

This invention relates to submarine boats. A submarine boat of the usual construction, even when running afloat, lies low in the water and, instead of riding the waves, plunges through them. This inability of such a craft to ride the waves is objectional for numerous reasons, among them the constant pounding and strain, the difficulty of steering, and the discomfort of those aboard. In accordance with my invention, I provide an appendage for the hull of a submarine boat at the bow thereof for augmenting the buoyancy of the bow and causing it to ride the waves instead of plunging through them. This buoyant appendage can, in the broader aspects of the invention, be disposed in any suitable manner to exert a lifting effect on the bow of the boat so as to cause the same to ride the waves, but, more specifically, I arrange this structure as an additional compartment mounted upon the upper part of the hull at the bow of the boat, forming, in effect, a superstructure able to withstand the same submergence pressure as the hull itself. This compartment, disposed to extend forwardly beyond the bow to the cut-water and having its forward portion disposed above the upper portion of the bow, so as to perform its function as above pointed out, is suitably connected with the interior of the boat, adding useful space, for instance as sleeping quarters for the crew.

In the drawings:

Figure 1 is a semi-diagrammatic longitudinal sectional view through the bow portion of a submarine boat embodying my invention; and

Fig. 2 is a transverse sectional view through the hull and the buoyant compartment.

The boat is generally of known construction and includes the hull 1 and a superstructure 2.

Upon the forward portion of the hull I mount a watertight compartment 3, this compartment being elongated and of substantially circular cross-section and being arranged with its axis fore-and-aft and in the vertical plane of the keel. This compartment, in the nature of an appendage to the hull, and of such strength as to withstand

the same submergence pressure as the hull, extends forwardly of the hull, tapering somewhat to the cut-water 5, its lower wall 3a being disposed at a decided inclination as shown.

The compartment 3 is provided aft with a hatch 7, of such size as to permit torpedoes to be introduced therethrough, and also with hatch 8 leading down into the hull for that and other purposes. These hatches also provide means of ingress and egress as will be clear.

With this arrangement, the compartment 3 adds materially to the useful space, for storage purposes and for use as quarters for the crew. With this object in view, I provide along each side of the major portion of this compartment, a plurality of bunks 10, releasing for other purposes the hull space ordinarily used for this purpose.

With the compartment 3 constructed and mounted in the manner illustrated and described, the normal buoyant effect at the bow is greatly augmented, the additional buoyancy thus provided being sufficient to cause the bow to ride the waves instead of plunging through them.

What I claim is:

1. In a submarine boat, a superstructure on the hull, and a water-tight compartment above the bow of the hull and secured thereto, said compartment forming a continuation of the super-structure and having its forward portion spaced above the forwardmost compartment of the hull.
2. In a submarine boat including a hull and a superstructure mounted thereon, a water tight compartment above the bow of the hull and secured thereto, said compartment projecting forwardly beyond the superstructure and extending beyond the outline of the upper portion of the hull.
3. In a submarine boat including a hull and a superstructure mounted thereon, a water tight compartment above the bow of the hull and secured thereto, said compartment projecting forwardly beyond the superstructure and having its forward portion above and spaced away from the forwardmost compartment of the hull.

4. In a submarine boat including a hull and a superstructure mounted thereon, a water tight compartment above the bow of the hull and secured thereto, said compartment opening into and projecting forwardly beyond the superstructure and beyond the main portion of the hull.
5. In a submarine boat including a hull and a superstructure mounted thereon, a water-
10 tight compartment above the bow of the hull and secured thereto, said compartment projecting forwardly beyond the superstructure and being disposed to enter the waves ahead of the main hull and to exert a lifting effect
15 enabling the boat to ride the waves when the boat is running afloat.
6. In a submarine boat including a hull and a superstructure mounted thereon, a water-
20 tight compartment of substantially circular cross-section and adapted to withstand full submergence pressure, said compartment being above the bow of the hull and secured thereto, the compartment projecting forwardly beyond the superstructure and being
25 disposed to enter the waves ahead of the main hull and to exert a lifting effect enabling the boat to ride the waves when running afloat.

In witness whereof, I hereunto subscribe
30 my name this 17th day of December, 1926.
ROBERT C. SIMPSON.
